(57) CLAIM

The ornamental design for an eyelash perm rod, as shown and described.

DESCRIPTION

FIG. 1 is perspective front view of an eyelash perm rod showing my new design;
FIG. 2 is a left view thereof;
FIG. 3 is a right view thereof;
FIG. 4 is a top view thereof;
FIG. 5 is a bottom view thereof;
FIG. 6 is a back view thereof; and,
FIG. 7 is a front view thereof.
The broken lines showing portions of the eyelash perm rod form no part of the claimed design.
